(57) **CLAIM**

The ornamental design for a control head for a mobile radio, as shown and described.

DESCRIPTION

FIG. 1 is a top, right, and front perspective view of a control head for a mobile radio showing my new design;

FIG. 2 is a front elevational view thereof;

FIG. 3 is a left elevational view thereof;

FIG. 4 is a right side elevational view thereof;

FIG. 5 is a top plan view thereof; and,

FIG. 6 is a bottom plan view thereof.

Broken lines are included for the purpose of illustrating environmental elements only and form no part of the claimed design.
